UNITED STATES PATENT OFFICE.

AUGUST EDWIN CARLBERG, OF WORCESTER, MASSACHUSETTS, ASSIGNOR TO WALDEN-WORCESTER, INC., OF WORCESTER, MASSACHUSETTS, A CORPORATION OF MASSACHUSETTS.

ATTACHMENT FOR WRENCHES.

1,424,712.

Specification of Letters Patent. Patented Aug. 1, 1922.

Application filed June 16, 1920. Serial No. 389,271.

To all whom it may concern:

Be it known that I, AUGUST EDWIN CARLBERG, a citizen of the United States, residing in Worcester, county of Worcester, and State 5 of Massachusetts, have invented certain new and useful Improvements in Attachments for Wrenches.

This invention relates to improvements in attachments for wrenches and has for its 10 object to provide a device adapted to be readily and quickly applied to a wrench of any suitable type to permit bolts and nuts to be assembled or separated.

The invention further has for its object 15 to provide a wrench attachment adapted to be secured to a socket wrench and having a nut or bolt holding socket adapted to register with the socket of the wrench.

Further objects of the invention are to 20 provide an attachment of this character which is simple in construction, efficient in operation, and economical to manufacture.

Other objects will in part be obvious and in part be pointed out hereinafter.

25 In the accompanying drawing, forming part of this application, wherein I have shown a preferred embodiment of my invention for the purpose of illustrating the principle thereof,

30 Figure 1 is an elevation showing the attachment applied to a socket wrench;

Fig. 2 is an enlarged side elevation of the attachment;

Fig. 3 is a plan view thereof, the caps being removed and

Fig. 4 is a sectional view taken on the line IV-IV of Fig. 2, the cap being removed.

Referring to the drawing, the attachment 40 is shown as including a yoke shaped frame comprising a rod 1 having an upwardly bent end 2 carrying a socket member 3 having a socket 4 formed in its inner end. As shown, the end of the upturned portion 2

45 extends within a recess 5 formed in the socket member which is secured in place by a pin 6 positioned within registering holes formed in the socket member and in the upturned end portion of the rod 1. Mounted

50 upon the other end of the rod 1, and secured thereto by a pin 7 is a support 8 having a U-shaped recess 9 formed in its upper end adapted to receive the shank of the wrench. A knurled cap 10, engaging a thread formed

upon the upper end of the support, serves 55 to hold the wrench in position within the recess.

Slidably supported within a hole extending through the support 8 is a rod 11 preferably having a head 12 at its outer end to 60 limit the inward movement of the rod. A block 13, secured to the inner end of the rod by a pin 14 has a U-shaped recess 15 formed in its upper end to receive the shank of a wrench. A knurled cap 16 is in threaded engagement with the upper end of the block 65 and serves to hold the wrench in place. The U-shaped recesses 9 and 15, in the support 8 and block 13, which are of the same size and shape, are in register with one another and with the socket 4 in the socket member 3. Surrounding the rod 11 is a coil spring 17 having its ends engaging the support 8 and the block 13 and serving to hold the rod normally in its innermost position. 70

Referring to Fig. 1 the attachment is shown, for purposes of illustration, as being applied to the shank of a socket wrench 18 of the speed type, but it will of course, be understood that the attachment may be used in connection with any other suitable type of wrench. To affix the attachment to the wrench it is merely necessary to remove the knurled caps 10 and 16 from the support 80 8 and block 13 and place the shank of the wrench within the U-shaped recesses 9 and 15 after which the caps are replaced to hold the shank of the wrench seated within the curved inner ends of the grooves in such a 85 manner that the wrench may be freely rotated with respect to the attachment. 90

In use, as shown in Fig. 1, the head of the bolt 19 is held within the socket 4 of the socket member 3 and the nut 20 is received within the socket of the wrench, whereupon the nut and bolt may be assembled or separated depending upon the direction of rotation of the wrench, the wrench being held in its proper operative 100 position by means of the spring 17. It will of course be understood that the positions of the nut and bolt may be the reverse of that shown in Fig. 1, the nut being held within the socket of the socket member and the head 105 of the bolt being received with the wrench socket. The wrench is detached from the attachment by removing the caps 10 and 16

and lifting the wrench from the U-shaped recesses.

By providing an attachment, such as hereinabove shown and described, which can be readily applied to an ordinary socket wrench, the necessity of having a special wrench for assembling or separating bolts and nuts is avoided and when the attachment is not in use the wrench may be employed in the usual manner.

While the attachment is adapted for use with many types of socket wrenches, it is particularly adapted for use in connection with wrenches of this type in which the socket is permanently secured to the shank.

While I have illustrated and described my invention in connection with a preferred embodiment thereof, it will be understood that I do not intend to limit myself to the specific embodiment shown, but that I intend to cover my invention broadly in whatever form its principles may be employed.

Having thus described my invention, I claim:

25. 1. An attachment for socket wrenches including a socket member and means adapted to receive the shank of a wrench and to hold the wrench with the socket thereof in register with the socket member, said means comprising a detachable member for permitting the removal or insertion of said shank within said means.
30. 2. An attachment for socket wrenches including a socket member and a plurality of spaced means adapted to receive the shank of a wrench and to hold the wrench with the socket thereof in register with the socket member, said means comprising a detachable member for permitting the removal or insertion of said shank within said means.
35. 3. An attachment for socket wrenches including a yoke-shaped frame provided with a socket at one of its ends and with means at its other end adapted to receive the shank of a wrench, an elongated member mounted upon said frame, said frame being provided with a guide for permitting longitudinal movement of said member with respect thereto, and means carried by said member adapted to receive the shank of a wrench.
40. 4. An attachment for socket wrenches including a yoke-shaped frame having a socket member secured to the end of one of the arms thereof and having a recess formed in the end of its other arm adapted to receive the shank of a wrench, an elongated member slidingly supported upon one of the arms of said frame, so as to be free to move in the direction of its longitudinal axis, a member carried by said sliding member having a recess formed therein adapted to receive the shank of a wrench, and means for holding the shank of the wrench in position within said recesses.
45. 5. An attachment for socket wrenches including a yoke-shaped frame having a socket member secured to the end of one of the arms thereof and having a recess formed in the end of its other arm adapted to receive the shank of a wrench, an elongated member slidingly supported upon one of the arms of said frame, so as to be free to move in the direction of its longitudinal axis, a member carried by said sliding member having a recess formed therein adapted to receive the shank of a wrench, and means for holding the shank of the wrench in position within said recesses.
50. 6. An attachment for socket wrenches including a yoke-shaped frame having a socket member secured to the end of one of the arms thereof and having a recess formed in the end of its other arm adapted to receive the shank of a wrench, an elongated member slidingly supported upon one of the arms of said frame, so as to be free to move in the direction of its longitudinal axis, a member carried by said sliding member having a recess formed therein adapted to receive the shank of a wrench, and means for holding the shank of the wrench in position within said recesses.
55. 7. An attachment for socket wrenches including a yoke-shaped frame having a socket member secured to the end of one of the arms thereof and having a recess formed in the end of its other arm adapted to receive the shank of a wrench, an elongated member slidingly supported upon one of the arms of said frame, so as to be free to move in the direction of its longitudinal axis, a member carried by said sliding member having a recess formed therein adapted to receive the shank of a wrench, and means for holding the shank of the wrench in position within said recesses.
60. 8. An attachment for socket wrenches including a yoke-shaped frame having a socket member secured to the end of one of the arms thereof and having a recess formed in the end of its other arm adapted to receive the shank of a wrench, an elongated member slidingly supported upon one of the arms of said frame, so as to be free to move in the direction of its longitudinal axis, a member carried by said sliding member having a recess formed therein adapted to receive the shank of a wrench, and means for holding the shank of the wrench in position within said recesses.
65. 9. An attachment for socket wrenches including a yoke-shaped frame having a socket member secured to the end of one of the arms thereof and having a recess formed in the end of its other arm adapted to receive the shank of a wrench, an elongated member slidingly supported upon one of the arms of said frame, so as to be free to move in the direction of its longitudinal axis, a member carried by said sliding member having a recess formed therein adapted to receive the shank of a wrench, and means for holding the shank of the wrench in position within said recesses.

cluding a yoke shaped frame having a socket member secured to the end of one of the arms thereof and having a recess formed in the end of its other arm, a cap detachably secured to the end of said other arm, a rod slidably mounted upon said other arm of the frame, a member carried by said rod and having a recess formed therein adapted to receive the shank of a wrench, and a cap detachably secured to said member.

6. An attachment for socket wrenches including a yoke-shaped frame having a socket at the end of one of its arms and having means at the end of the other of its arms to receive the shank of a wrench, a rod slidably mounted within a hole formed in said other arm of the frame, a member secured to the inner end of said rod having means to receive the shank of a wrench, and a spring normally tending to cause inward movement of said rod, said rod being provided with means at its outer end to limit the inward movement thereof.

7. An attachment for socket wrenches including a rod, a socket member secured to one end thereof, a member fixed to the other end of said rod having a recess adapted to receive the shank of a wrench, said fixed member having an opening parallel to the said shank, a member extending through said opening and slidably longitudinally therein, a member secured to said slidable member having a recess adapted to receive the shank of a wrench and means for holding the shank of the wrench in position within said recesses.

8. An attachment for socket wrenches including a rod, a socket member secured to one end thereof, a member fixed to the other end of said rod having a recess adapted to receive the shank of a wrench, a slidable member carried by said fixed member and extending parallel to said shank, a member secured to said slidable member having a recess adapted to receive the shank of a wrench, means for holding the shank in position within said recesses, and a coil spring surrounding said slidable member and engaging the member carried thereby and said fixed member.

9. An attachment for socket wrenches consisting of a frame having a recessed portion at one end for receiving the shank of a wrench, and a socket at the other for receiving a bolt or nut, a rod extending from said one end of the yoke toward the other, means for mounting said rod for longitudinal movement in said yoke, a member provided on the said rod and having a recess for receiving said shank, a spring concentric with said rod for biasing said member towards said socket, and means for co-operating with the said recessed portions of said frame and member, whereby said shank may be removably secured in said recesses.

10. An attachment for socket wrenches consisting of a frame having a recessed portion at one end for receiving the shank of a wrench, and a socket at the other for receiving a bolt or nut, a member having a recessed portion for receiving said shank, means for guiding said member for movement parallel to said shank, and means for co-operating with the said recessed portions of said frame and member, whereby said shank may be removably secured in said recesses. 10

AUGUST EDWIN CARLBERG.
